UNITED STATES PATENT OFFICE.

FREDERICK E. STANLEY, OF WATERBURY, CONNECTICUT, ASSIGNOR TO SCOVILL MANUFACTURING COMPANY, OF WATERBURY, CONNECTICUT, A CORPORATION OF CONNECTICUT.

BUTTON-SETTING MACHINE.

SPECIFICATION forming part of Letters Patent No. 732,230, dated June 30, 1903.

Application filed August 27, 1901. Serial No. 73,488. (No model.)

To all whom it may concern:

Be it known that I, FREDERICK E. STANLEY, a citizen of the United States, residing at Waterbury, in the county of New Haven and 5 State of Connecticut, have invented a certain new and useful Improvement in Button-Setting Machines, of which the following is a full, clear, and exact description.

This invention relates to machines for applying buttons to garments by means of tacks and similar metal fastenings, and has special reference to the means for presenting the fastenings to the plunger or setting device and carrying it into position to be affixed to 15 the garment.

The invention consists of a pair of automatic spring-pressed jaws alined with the setting mechanism, adapted to receive the tack or other fastening from the feeding 20 mechanism, present it to the setting mechanism, and release it as it is about to be affixed to the garment and return to position to receive another fastening, all as I will now proceed more particularly to set forth and 25 finally claim.

In the accompanying drawings, illustrating my invention, in the several figures of which like parts are similarly designated, Figure 1 is a side elevation of the head of one form of 30 machine embodying my invention. Fig. 2 is a front elevation thereof. Fig. 3 is a front perspective view of the spring-pressed jaws detached and in condition to receive the fastening. Fig. 4 is a rear perspective view 35 of the spring-pressed jaws detached and in condition to discharge the fastening. Fig. 5 is a top plan view of the said jaws detached.

The base *a*, the anvil mechanism *b*, the gooseneck *c*, hopper *d* for containing and 40 feeding the fastenings, such as tacks, the race-way *e* for delivering the tacks to the tack-holder, the hopper-actuating mechanism *f*, the vertically - reciprocating plunger *g*, its actuating-lever *h*, the tack-switch *i*, and its 45 actuating mechanism may be of any usual or, as shown, preferred construction and need no further description for the purposes of this specification excepting to note that the hopper-actuating mechanism, consisting, es-

sentially, of a pawl and ratchet, is controlled 50 by a lever *j*, vibrated by the lever *h*, and the switch is vibrated by a rod *k*, connected with the ratchet and deriving motion therefrom. The mechanism described serves to feed a tack to the tack-holder, herein shown as 55 spring-pressed jaws, presenting it point down to the said holder, by which, in conjunction with the plunger, it is presented to a button bottom up in the anvil and affixed to the garment which is placed over the button, the 60 holder meanwhile freeing or delivering the tack and receding from the anvil and again going back into position to receive another tack for the repetition of these operations.

The tack-holder is composed of a pair of 65 jaws *l* of complemental construction, pivotally jointed at their upper ends, as by a screw *m*, and having adjacent parallel cut-away portions to form a slot *n*, and their lower ends *o* arranged at right angles and provided with 70 complemental countersunk recesses to form an opening *p* to receive and support a tack by its head and with its point downward. These jaws are normally closed, as in Figs. 1, 2, 3, and 5, by means of a spring *r* or 75 equivalent device attached to and carried by them. These jaws are mounted upon the head of the gooseneck by means of screws *s* and *t*, one or both of which may be provided with a washer *u*, interposed between its 80 head and the jaws and of a diameter commensurate with remaining in engagement with the jaws in the spread of the jaws in discharging a tack. The jaws are capable of 85 vertical movement upon the head, and such movement is limited by the screws *s* and *t* in their relative arrangement within the slot *n* and by pins *v* on the jaws, which come into contact with the head. The jaws are normally elevated, as in Figs. 1 and 2, by a spring 90 *w*, supported upon a pin *x*, rising from the head or gooseneck. As a tack is delivered to the holder from the raceway with its point down, the plunger *g* is caused to descend, and coming into contact with the head of the tack 95 within the jaws and firmly holding it therein it carries down the jaws until the pressure overcomes the jaw-spring or until their descent

is arrested by the screw *s* coming into contact with the upper end of the slot *n*, and the plunger in its further descent pressing upon the jaws causes them to separate or swing 5 apart or open laterally against the tension of the spring *r*, whereby the tack is released and is free to be acted upon by the plunger to connect it with the button by upsetting its point within said button in any usual 10 way. The parts are timed to release the tack by the opening of the jaws at the time when the tack-point has pierced the garment and entered the button, or thereabout, and so that the tack will remain upright when un- 15 supported by the jaws and in position to be set by the plunger. As soon as the jaws fully separate or open and are thus freed from the pressure of the descending plunger they rise under the tension of spring *w* and re- 20 sume their normal position opposite the discharge end of the raceway, and when the plunger completes its return stroke and clears the jaws said jaws come together again under pressure of spring *r* and are ready to re- 25 ceive the next tack for the repetition of these operations. Thus a very simple and efficient tack-holder is provided for this class of button-setting machines.

What I claim is—

In a button-setting machine, the combination with the head of the machine, and a reciprocating plunger arranged therein, of a tack-holder consisting of a pair of jaws directly pivoted together at their upper ends, and having their lower portions extending beneath the head and in the line of movement of the plunger and adapted to receive and support a tack with its head uppermost, and a spring normally closing said jaws, said tack-holder being mounted to slide on the outer front face of the head of the machine, the movement of the tack-holder for placing a tack being effected by contact of the plunger therewith as it descends and the parting of the jaws to release the tack also being effected by said plunger in its further descent, and means for normally drawing up the tack-holder and serving to retract it as the plunger ascends.

In testimony whereof I have hereunto set my hand this 20th day of August, A. D. 1901.

FREDERICK E. STANLEY.
